COUCH BED

Joseph Martin, Laurelton, N. Y., assignor to
 United States Cabinet Bed Co., Brooklyn, N. Y.,
 a corporation of New York

Application February 15, 1933, Serial No. 656,790

9 Claims. (Cl. 5—17)

This invention relates to couch beds in general and more especially to combination single and double beds.

Among the objects of the present invention, it is 5 aimed to provide an improved combination single and double bed consisting of a fixed main frame, a movable secondary frame operatively connected to said main frame to be moved under said main frame into single bed formation and to be moved 10 to one side of said main frame for double bed formation, and an extension bed section removably connected to said secondary frame to cooperate with said main frame to form a double bed when disposed adjacent to said main frame and 15 to form a separable bed, in which latter case the secondary frame constitutes a convenient means for anchoring the extension bed in concealed position under said main frame when not in use.

It is still another object of the present invention to provide an improved combination single and double bed consisting of a fixed main bed section, an auxiliary bed section, a frame operatively connected to said main bed section when disposed in extended position to removably anchor said auxiliary bed section adjacent 25 to said main bed section in double bed formation and when housed under said main bed section adapted to anchor said auxiliary bed section in housed position under said main bed section.

It is still another object of the present invention to provide an improved means for operatively connecting to a main bed section a carriage or frame adapted to anchor an auxiliary bed section in housed position under said main bed section. 30

It is still another object of the present invention to provide an improved actuating means for catapulting or projecting to one side of a main bed section an auxiliary bed section normally housed within said main bed section.

It is still another object of the present invention to provide an improved connecting means for removably connecting the auxiliary bed section to a carriage which is operatively connected to a main bed section to be moved into and out of the same, which connecting means are not only simple in construction but in addition can be produced at low cost.

These and other features, capabilities and advantages of the invention will appear from the 55 subjoined detail description of one specific em-

bodiment thereof illustrated in the accompanying drawings, in which

Figure 1 is a perspective of a couch bed made according to the present invention;

Fig. 2 is an enlarged fragmental plane view 5 showing the bed sections in double bed formation;

Fig. 3 is a similar enlarged fragmental end elevation partly in section showing the bed sections in double bed formation; and

Fig. 4 is a fragmental section on the line 4—4 of Fig. 3.

In the embodiment illustrated, there is provided a main bed section 1, which in the present instance also constitutes the main frame, and a 15 removable bed section or extension bed section 2 which may be moved into and out of said main bed section 1.

The main bed section 1 preferably is provided with four standards or vertically extending angle 20 irons 3 which are connected to the corners of the rectangular metal frame 4 which is preferably provided with a wire support 5 and coil springs 6 forming the inner springs of a built-in mattress 7 for the main bed section 1.

The rectangular frame 4 preferably as illustrated in Fig. 3, has along its outer longitudinal edge a bar 8 cooperating with the mattress 7 to extend beyond the outer side of the frame 4. On the other hand, the end boards 9 of the main 30 frame 1, see particularly Fig. 1, extend beyond the outer faces of the corner standards 4 so that their front ends are in alinement with the upper face of the mattress 7.

In single bed formation or couch formation, 35 there is loosely laid or separably laid on the mattress 7, a second mattress 10 which mattress in double bed formation is removed from the mattress 7 and laid on the auxiliary bed section 2, as indicated in Fig. 3.

The main bed section preferably has small ornamental feet 11 formed at the bottom of the standards 3 as indicated in Fig. 1 which however are preferably not provided with rollers to form a substantial anchor with the floor and thus co-operate with the parts of the couch bed now to be described.

The auxiliary bed section 2 preferably has a longitudinal frame 12, the outer edge of which is provided with a front board 13 having at its ends 50 the vertically extending angle irons 14 provided with bearings at their lower ends for the large rollers 14a.

Preferably also adjacent to the rear side of the frame 12 and substantially five-sixths of the 55

distance of the front face to the rear face of the frame 12, there are provided the vertically extending standards 15 secured to the end bars 16 of the frame 12. To the side of the standards 15 and extending rearwardly therefrom, there are provided the brackets 17 having at their lower ends bearings for the small rollers 18. These standards 15 are further provided with studs 19 extending rearwardly from the standards 15 and having enlarged heads 20 formed thereon. These studs 19 are adapted to engage the V-shaped recesses 21 formed to recede from the upper edge of the longitudinally extending bar 22 of the carriage 23 which has vertically extending standards 24 extending downwardly therefrom having bearing brackets 25 formed thereon to receive the large rollers 26. The standards 24 are preferably located near the ends of the bar 22 but spaced from the recesses 21.

20 The bar 22 is an angle iron having a horizontally extending portion 27 to which is connected the means for maintaining the carriage 23 in upright position and also for controlling its movement into and out of said main bed section 1. The connecting means consist essentially of a pair of connecting links, to wit the two long links 28 and 29 and the two short links 30 and 31 respectively. One of the links 29 is pivotally connected to the portion 27 of the bar 22 spaced about one-third of the length of the bar 22 from one end thereof and one end of the link 31 is pivotally connected to the portion 27 of the bar 22 spaced about one-third of the length of the bar 22 from the other end of the same and the other end of the link 29 is pivotally connected to the front end of the link 30 while the other end of the link 31 is pivotally connected to the link 28. The links 28 and 29 are pivotally connected to one another at a point which is spaced about one-fourth of the length of the link 28 from its connection with the link 31 and which is spaced about one-fourth of the length of the link 29 from its connection with the link 30.

45 The rear end of the link 28 is pivotally connected to the horizontal portion 32 of the angle iron 33 secured to the rear corner standards 3 of the main bed section 1. The connection of the link 28 with the angle iron 33 is disposed at a point spaced about one-third of the length 50 of the main bed section 1 from the right end thereof looking at Fig. 1.

The link 30 is pivotally connected to the portion 32 of the angle iron 33 at a point spaced about one-third of the length of the main bed section 1 from the left end thereof looking at Fig. 1.

55 For anchoring the carriage 23 in position in the main bed section 1, with or without the auxiliary bed section 2, there is provided the arm 35 which is fixed on the shaft 36 journaled in the rear corner uprights 3. The arm 35 is preferably composed of flat stock and is provided with a vertically extending head portion 37 having a front inclined cam face 38 and a rear shoulder 39. The arm 35 is preferably disposed at or near the middle of the shaft 36 so that its head 37 can effectively cooperate with the bar 22 of the carriage 23 now to be described.

60 In the raised position as indicated in Fig. 3, the shoulder 39 is in position to engage the front face of the bar 22 and thereby anchor the carriage 23 against accidental displacement. In order normally to maintain the shoulder 39 in such raised position, the springs 40 are provided which connect the levers 41 and 42 with the crosspieces 43 at each end of the main bed sec-

tion 1. The levers 41 and 42 are similarly fixed to the shaft 36 and disposed adjacent to the ends of the main bed section 1. These levers 41 and 42 similar to arm 35 extend forwardly and have at their front ends the foot engaging pedals 44. 5

When the carriage 23 is moved inwardly into the main bed section 1 so that its bar 22 engages the head 37, it will first engage the cam face 38 to depress the head 37 against the tension of the springs 40 and thereupon slide over the head 37 10 to and beyond the shoulder 39 when the springs 40 will cause the shaft 36 to rock in turn to raise the head 37 and cause the shoulder 39 to engage the front face of the bar 22 of the carriage 23. In turn, when it is desired to release the carriage 15 23, it is of course only necessary to engage either of the pedals 44 and depress the same thereby to rock the shaft 36 and in turn to depress the head 37 out of engagement with the bar 22, when the carriage 23 will be free to be moved out of the 20 main bed section 1.

In order automatically to eject the carriage 23 when the pedals 44 are so depressed, there is provided a spring 45 which connects the link 30 with the end of the abutment 46 extending from 25 the horizontal portion 32 of the angle iron 33. This spring 45 is of course heavy enough to perform the work required of it. It has been found in practice that a spring of the dimensions indicated in the drawings as compared to the structure illustrated is sufficient to eject not only the carriage 23 but also the carriage 23 with the bed section 1 attached thereto as illustrated in Fig. 2.

30 From the foregoing, it will appear that the spring 45 and links 28, 29, 30 and 31 will co-operate to eject the carriage 23 when the arm 35 is depressed as above described by the actuation of either the lever 41 or the lever 42. 35

It will also appear that when the carriage 23 is moved into the bed section 1 with or without 40 the bed section 2, that after the arm 35 engages the bar 22 of the carriage 23, it will anchor the same against ejection by the spring 45 until the arm 35 is again depressed.

In order to determine the position of the bed 45 section 2 relative to the bed section 1 when ejected into the position illustrated in Fig. 2, the stops or limiting means now to be described are provided.

50 Each of the front corner uprights 3 of the main bed section 1 is provided with a vertically extending portion 47 extending inwardly toward one another as illustrated in Fig. 2. The ends of the bar 22 of the carriage 23 are provided with the rearwardly extending arms 48, each of 55 which has formed thereon two studs, to wit the studs 49 and 50. Each set of studs 49 and 50 travels in a slot 51 of a bar 52 extending rearwardly from the carriage 23. The bars 52, see particularly Fig. 2, have at their extreme inner 60 ends laterally extending portions 53. On the forward face of each of the portions 53, there is provided a suitable resilient buffer 54 adapted to strike the rear face of an upright portion 47. The upright portions 47 as indicated in Fig. 3 65 are cut away above the edge 47^a to clear the end bars 16 of the carriage when the carriage is actuated into and out of the chamber formed by the bed section 1.

70 In other words, the slots 51 and studs 49 and 50 are so positioned relative to one another and relative to the length of the bars 52 and the arms 48 that the engagement of the portions 53 by the rear wall of the main bed section 1 when the carriage 23 is moved inwardly will permit 75

the bar 22 to pass over and into engagement with the shoulder 39 of the arm 35 and on the other hand when the auxiliary bed section 2 is moved outwardly, it will permit the carriage 23 to move 5 far enough beyond the edge of the main bed section 1 so that the mattresses 7 and 10 may be disposed adjacent to one another in the position indicated in Fig. 3.

From the foregoing, it will thus appear that 10 the present invention contemplates an improved combination single and double bed which includes a twin bed arrangement in which the auxiliary bed section may be separated from the main bed section and be used independent of, 15 and separated from the main bed section, which includes a catapult bed arrangement in which the auxiliary bed section may at will be automatically ejected from the main bed section and which includes a carriage operatively connected 20 to the main bed section to which an auxiliary bed section may be connected to facilitate anchoring the auxiliary bed section to the main bed section in double bed formation as well as in couch formation.

25 It will also appear from the foregoing that the links 28, 29, 30 and 31 cooperate not only to guide and control the position of the carriage 23 and therewith of the auxiliary bed section 2 relative to the main bed section 1 but that it also 30 cooperates with the spring 45 to eject the carriage 23 automatically when the locking mechanism is actuated and that it also cooperates to position the carriage 23 to be automatically anchored by the head 37 of the locking mechanism. 35 To facilitate smooth operation of the carriage 23 and auxiliary bed section 2 during ejection or return movement, the position of the rollers 18 is such that they will not engage the floor but only the rollers 26 and of course the rollers 14a. 40 On the other hand, when the auxiliary bed section 2 is separated from the carriage 23, the auxiliary bed section 2 will be supported on the rollers 18 and 14a, the rollers 18 thus merely serving as auxiliary rollers to cooperate with the 45 rollers 14a when the auxiliary bed section 2 is separated from the carriage 23. In operation, assuming the bed section 2 to be inside the bed section 1 and that the shoulder 39 of the latch head 37 engages the bar 22 to anchor the carriage 50 and therewith the bed section 2 in single bed formation, it will only be necessary to depress one of the pedals 44 in turn to depress the latch head 37 out of engagement with the bar 22 when the spring 45 will be free to eject the carriage 55 23 and therewith the movable bed section 2. In its outward movement, the levers 28, 30, 29 and 31 will then open in turn to cause the pairs of bars 52, 48 to move into their extended position, that shown in Fig. 3, where the bed section 2 will 60 be disposed adjacent the bed section 1 in double bed formation. The position of the bed section 2 will be determined by the buffers 54 engaging the flanges 47.

In this extended position of the bed section 2, 65 it will of course be a simple matter to raise the bed section 2 and therewith its studs 19 out of engagement with the recesses 21 entirely to separate the bed section 2 from the bed section 1.

On the other hand, after the bed section 2 70 has been connected to the carriage 23 by the positioning of the studs 19 in the recesses 21, it will only be necessary thereupon when it is desired to actuate the bed section 2 into single bed formation inside the bed section 1 to move the 75 bed section 2 into the chamber formed in bed

section 1 until the latch head 37 again engages the bar 22 of the carriage 23.

It is obvious that various changes and modifications may be made to the details of construction without departing from the general 5 spirit of the invention as set forth in the appended claims.

I claim:

1. A main bed section having a chamber, a carriage, links for operatively connecting the carriage inside of said main bed section to move into and out of said chamber, an auxiliary bed section, rollers on which said auxiliary bed section and carriage are mounted to facilitate moving the same along the floor relative to said main bed section as an anchor, said carriage having a longitudinally extending bar having recesses formed along its upper edge, studs on said auxiliary bed section adapted to rest in said recesses, and heads on said studs to engage the side of 20 said bar to form an abutment for carrying the auxiliary bed section with said carriage during movement thereof.

2. A main bed section having a chamber, a carriage, links for operatively connecting the carriage inside of said main bed section to move into and out of said chamber, an auxiliary bed section, rollers on which said auxiliary bed section and carriage are mounted to facilitate moving the same along the floor relative to said main 25 bed section as an anchor, said carriage having a longitudinally extending bar having recesses formed along its upper edge, studs extending from one side of said auxiliary bed section and adapted to rest in said recesses, and heads on said studs, 30 the heads and side of said auxiliary bed section functioning as abutments to facilitate carrying the auxiliary bed section with said carriage during movement thereof.

3. A main bed section having a chamber, a flange forming bar formed on said main bed section, a carriage having a flange forming bar, two pairs of links, each pair consisting of a link 40 pivotally connected to the flange forming bar of said main bed section and of another link 45 pivotally connected to the flange forming bar of said carriage, a link of each pair pivotally connected to a link of the other pair, the links of each pair being operatively connected to one another, an abutment extending forwardly from 50 the rear wall of said main bed section, and a spring connecting said abutment with one of said links to urge such link into extended position and thereby to actuate said links in turn to eject said carriage. 55

4. A main bed section having a rear wall and two side walls to form a chamber open at the front side, a carriage, two pairs of links, each pair consisting of a long link and a short link pivotally connected to one another, the long 60 links being pivotally connected to one another, the long link of one pair being pivotally connected to said rear wall and the short link of such pair being pivotally connected to said carriage, the long link of the other pair being pivotally connected to said carriage and the short link of such other pair being pivotally connected to said rear wall, an ejecting spring connected to said rear wall and to the short link of such other pair to urge said latter short link outwardly 70 from said wall, and an auxiliary bed section connected to said carriage. 65

5. A main bed section having a chamber open at the front side, a carriage, an ejector operatively connecting said carriage with said section 75

to eject said carriage out of said chamber, an abutment on said carriage, a rock shaft on said main bed section, a catch fixed to said rock shaft, levers fixed to said rock shaft, pedals on said levers extending laterally from beneath the lower edge of the side of said main bed section, a spring for normally maintaining said catch in position to engage said carriage abutment and anchor said carriage against ejection but yieldable in response to the actuation of either of said levers to release said carriage abutment and thereupon liberate said ejector to eject said carriage, and an auxiliary bed section adapted to be connected to said carriage.

15. 6. A main bed section, a carriage, an ejector operatively connecting said carriage with said section to eject said carriage relative to said main section, an abutment on said carriage, a rock shaft on said main bed section, a catch fixed to said rock shaft, levers fixed to said rock shaft, pedals on said levers extending laterally from the lower edge of the side of said main bed section, springs for normally maintaining said catch in position to engage said carriage abutment and anchor said carriage against ejection but yieldable in response to the actuation of either of said levers to release said carriage abutment and thereupon liberate said ejector to eject said carriage, and an auxiliary bed section adapted to be connected to said carriage, said catch having a cam thereon to be engaged by said carriage abutment when said carriage is moved into said chamber to actuate said catch against the tension of said spring until said cam clears said abutment and permits said catch to engage said abutment.

7. A main bed section having a chamber, a carriage, two pairs of links, each pair consisting of a long link and a short link pivotally connected to one another, the long links being pivotally connected to one another, the long link of one pair being pivotally connected to said section and the short link of such pair being pivotally connected to said carriage, the long link of the other pair being pivotally connected to said carriage and the short link of such other pair being pivotally connected to said section, an ejecting spring connecting said section to said short link of such other pair near the outer end of said latter short link to urge such link into forwardly

extended position and thereby to actuate said links in turn to eject said carriage, and an auxiliary bed section connected to said carriage.

8. A main bed section having a chamber, a carriage, two pairs of links, each pair consisting of a long link and a short link pivotally connected to one another, the long links being pivotally connected to one another, the long link of one pair being pivotally connected to said section and the short link of such pair being pivotally connected to said carriage, the long link of the other pair being pivotally connected to said carriage and the short link of such other pair being pivotally connected to said section, an ejecting spring connecting said section to the short link of such other pair, an auxiliary bed section connected to said carriage, and means for normally anchoring said carriage in said chamber against ejection but yieldable to release said carriage and thereupon liberate said ejecting spring to eject said carriage.

9. In a convertible bed, in combination, a main bed section having an open front, an auxiliary bed section movable through the said open front from single bed position to double bed position, 25 said auxiliary bed section including a carrier, means by which the carrier is readily detachable from the remainder of the auxiliary section, a combined spring actuated ejector and equalizer connected to the rear of the main section and 30 to the carrier, a rock shaft on the rear of said main section, a catch rigid with said shaft, levers at the respective ends of said shaft, pedals on said levers extending laterally beneath the lower edges of the ends of the main section, an abutment on said auxiliary section, spring means normally maintaining said catch in position to engage said abutment and anchor said auxiliary section against ejection but yieldable in response 40 to the actuation of either of said pedals to release said abutment and thereupon liberate said ejector to eject said auxiliary section, said catch having a cam thereon to be engaged by said abutment when said auxiliary section is moved 45 into said main section to actuate said catch against the tension of the spring means until said cam clears said abutment and permits said catch to engage said abutment.

JOSEPH MARTIN. 50
